UNITED STATES PATENT OFFICE.

EDWARD G. COOK, OF LONG ISLAND CITY, NEW YORK, ASSIGNOR, BY MESNE ASSIGNMENTS, TO COPPER PRODUCTS COMPANY, A CORPORATION OF MAINE.

PROCESS AND APPARATUS FOR ELECTRODEPOSITION UNDER COMPRESSION.

1,271,136.

Specification of Letters Patent.

Patented July 2, 1918.

Application filed May 13, 1916, Serial No. 97,227. Renewed May 11, 1918. Serial No. 234,016.

To all whom it may concern:

Be it known that I, EDWARD G. COOK, a citizen of the United States, residing in Long Island City, in the county of Queens 5 and State of New York, have invented certain new and useful Improvements in Processes and Apparatus for Electrodeposition Under Compression, of which the following is a specification.

10 In the electro-deposition of metals it has been found that frequently by vagaries in the current, or unknown conditions in the electrolytic-bath, that the metals deposited are spongy, non-solid and not as homogeneous as is desired.

15 The objects of my invention, are to provide a new and improved method or process, and a new and improved apparatus for carrying the same into effect, wherein and whereby electrolytically-deposited metallic articles of all forms, may be solidly and homogeneously formed, in a cheap and efficient manner.

20 My improved method and process of so forming articles by electro-deposition may be carried out by many various and widely diverse machines and apparatus; several forms of which, of my invention are herein disclosed.

25 Such devices as shown herein are particularly designed and adapted for the electro-deposition of annular-rings, which may be used for various purposes; but in the forms shown, the same are more particularly 30 adapted and designed for the production of the driving-rings of soft copper, etc., to be used as driving-rings upon artillery projectiles to take the rifling of the cannon-bore, and give the projectile proper rotation.

35 My said method and process, and apparatus for carrying such process and method into effect are fully shown and described in the following specification, of which the accompanying drawings form a part, and 40 wherein:—

45 Figure 1 is an end view in substantially central longitudinal section, on the line *a—a* of Fig. 2, looking from the left thereof in the direction of the arrow, of an electrolytic-bath adapted for the formation of annular-rings by my improved process herein disclosed.

50 Fig. 2 is a view of such structure looking from the right of Fig. 1, taken in substantially central vertical section, showing an

electrolytic-bath adapted for the simultaneous formation of two rings.

Fig. 3 is an end view partially in section, and on an enlarged scale of a portion of the simplest form of apparatus of my invention 60 for carrying such improved metal-depositing, densifying and consolidated method of process into effect; and Fig. 4 is a view in detail of a slightly modified form of construction, similar to the top portion of 65 Fig. 3.

Fig. 5 is an end view similar to that shown in Fig. 1 of a second modified form of construction, of that portion of the mechanism shown in such Fig. 1. 70

Fig. 6 is a top plan view of the entire structure and apparatus, a portion only of which is shown in Fig. 5.

Fig. 7 is a view similar to Fig. 6 showing an apparatus for simultaneously forming 75 two rings instead of one, the pressure upon each of which may be varied; and Fig. 8 is a top plan view similar to Fig. 7, save that six rings are being simultaneously formed under equal densifying and consolidating 80 pressure.

While the apparatus shown is especially designed for the formation of annular-rings, my improved method and process herein disclosed is not limited to such use, but may be 85 used for the formation by electrolytic-deposition of densified and consolidated articles of any desired shape or form; but in the formation of rings, I prefer to form the same in the manner following: 90

Referring to the drawings:—

In Fig. 1 the reference numeral 1, designates the electrolytic-bath-receptacle, or tank containing electrolytic-liquid, usually up to the height of the line *b—b* so as to immerse 95 the cathode *C*—, to a point just below the journals 6 thereof resting in the journal slots 2, which slots are open at the top and are formed in the end walls 3, of the receptacle. Located in the tank, usually supported on 100 the bottom by insulating-studs 4, is the anode *A*+, usually in the form of a plate. The cathode *C*—, is usually formed of brass, or other suitable metal or alloy having high 105 electric conductivity, and consists of the central conducting-cylinder or mandrel 5, having at either end the integrally formed journals 6 and 6', removably and revolvably fitting in the journal slots 2; which are preferably rounded outwardly toward the front, 110

as indicated at 2' (Fig. 1) so as to facilitate the insertion and removal of the cathode C— without interference with the outer end of 22.

5 Removably secured upon the journal 6 is a pulley or gear-wheel 7, by means of which such cathode may be rotated.

The other journal 6', has in contact therewith a commutator-contact-spring 8, usually supported upon a bracket 8', on the receptacle-wall leading from which spring to the minus-pole (—) 9 of the electric-generator G, is the conducting-wire 10; while from the plus-pole (+) 11, an insulated conducting-wire 12, connects with the anode A+. On the journal 6' is removably secured a collar 13, to prevent end thrust during rotation of the cathode.

To produce rings by my improved electrolytic process I superpose alternately upon the conducting-cylinder a plurality of alternately arranged insulating mold-rings 14, of hard-rubber, glass or other suitable insulating material; between which are interposed 25 conducting mold-blank-rings 15, usually of lead, or other comparatively soft and easily fusible metal; and when ready to be inserted in the electrolytic-bath, a peripheral-annular-mold-space or cavity 16, of the 30 shape and contour of the ring to be electrolytically produced, is left between the insulating-mold-rings 14; and upon insertion in the bath; upon turning on the current, and rotating the cathode C—, the electrolytic rings 17 required, are formed by electro-deposition upon the conducting-mold-rings 15, in the annular mold-space or cavities 16, until the same are completely filled.

Thus far as described the method and 40 apparatus herein described and shown is not of my invention; but I have discovered and demonstrated that the sponginess sometimes found in electro-deposition in processes of the character used herein; may be 45 removed by burnishing or smearing mechanical-pressure exerted upon the article being formed during its deposition, in such manner that the laminae of micrometric thickness deposited, as fast as deposited, 50 are mechanically densified, consolidated and compressed one upon the other, in such manner as to produce a deposited article of a non-porous and homogeneous solid structure.

55 In the case of articles to be so electrolytically produced which are not of annular form, such for instance as flat articles, this pressure may, in carrying out the method or process herein disclosed, be 60 brought about by a reciprocating or vibratory motion; but I have not deemed it necessary herein to show mechanism and apparatus therefor, as from the disclosure the mechanism for so doing could be easily designed by any mechanic skilled in the art.

As shown in Figs. 1, 2, 3 and 4 the means which I use for bringing about the mechanical pressure upon the article (in this case the annular-rings 17 being deposited) in this the simplest form of my apparatus, 70 is a pressure-spring 18, secured to a bracket or upward extension of the back-wall 3' of the receptacle or bath-tank 1, by means of screws 20; which pressure-member or spring 18 is formed of any suitable resilient spring-metal; and is tensioned to the proper pressure by tension-screws 21, located in the forward extensions 22 of the brackets 19, as clearly indicated in Figs. 1, 2 and 4. Such pressure-spring is preferably provided 80 with a contracting pressure burnishing surface 23 of segmental concave contour (Figs. 1 and 3) in order to contact with the annular-ring 17 to be electrolytically deposited throughout a considerable portion of its periphery.

The operation of the pressure of the consolidating spring 18 is clearly indicated in Fig. 3, the deposited micrometric laminae in same as well as in Figs. 4 and 5, being 90 shown greatly enlarged in order to bring out the metal densifying and consolidating action of my improved process and apparatus herein disclosed.

When metal burnishing-springs, wheels 95 or other devices are used to bring about the compression, the corrosive action of the chemicals of the electrolytic-bath are liable to corrode, roughen and greatly deteriorate the burnishing surface in contact with the 100 deposit; and in such cases, instead of the spring 18 being in direct contact with the article or ring being molded a proper burnishing block 24 (Fig. 4) of any suitable hard and exceedingly smooth surfaced 105 material such as glass, agate, etc., unaffected by the chemicals of the bath may be secured in any desired manner to the working end of such spring 18; and the same is usually of the form shown in (Fig. 110 4), consisting of a base 25, having a securing shank 26 fitting in a cavity 27 formed in the end of the pressure-spring 18, and secured therein by means of a screw 28, or in any other desired manner.

In the simplest form of apparatus for carrying into effect my improved method of electrodeposition herein disclosed; it will be seen the cathode C— rotating in the direction of the arrow (Figs. 1 and 3) will 120 cause the burnishing portion of the pressure-spring to press upon the article, in this case the annular rings being deposited, with a burnishing, dragging, compressing and consolidating pressure and action; and I have found that in the composition of rings for various purposes where different degrees of hardness is required this may be varied in three ways; first by varying the pressure upon the burnishing and compression-spring 125 130

18 by proper manipulation of the tension-screws 21; second by varying the speed of rotation of the cathode, and third a combination of variation of both such tensioning 5 and rotation.

In Figs. 1 and 6 I have shown an apparatus for forming one ring at a time, while in Figs. 2 and 7 I have shown an apparatus for forming two rings simultaneously.

The modified form of apparatus shown in Figs. 5 to 8 inclusive differs from that shown in Figs. 1 to 4 inclusive in that the consolidating pressure exerted upon the annular 15 rings being formed instead of being brought about thereon by a stationary burnishing member is exerted upon the article deposited by a rapidly positively rotated burnishing or deposition consolidating pressure-wheel

20 30, and in my preferred form of construction, wherein a plurality of rings are deposited at the same time (shown in Fig. 7) the brackets 19, are provided with backwardly extending brackets 31, having journal-boxes in which are revolvably mounted the main or drive-shaft 32 having the main 25 drive-wheel 33, driven by the belt 34, and also having mounted thereon the drive wheels 35 and 35' carrying the belts 36 and 36' driving the drive-wheels 37 and 37', driving the pressure-wheel-shaft or shafts 38, revolvably mounted in the outer ends of the vibrating-lever or levers 39 (Figs. 5 to 30 35) forced downward toward the ring being deposited by the pressure springs 18', tensioned by the screws 21, upon which shaft or shafts 38 are rigidly mounted the pressure-wheels 30. In the case of the two ring forming apparatus shown in Fig. 7, the 40 two shafts 38 are separate one from the other, and thus may be individually tensioned by proper manipulation of the tensioning-screws; whereby one ring deposited may have a different pressure exerted upon 45 it than that upon the other ring being formed simultaneously therewith.

The construction shown in Fig. 8 differs only from that shown in Fig. 7, in that instead of two rings being simultaneously 50 formed there are six; and also in that the tension exerted upon each of such rings is the same; there being but two tension screws 21, one for each end of the pressure-wheel-shaft 38.

55 It will be seen that in all of the constructions shown in Figs. 5 to 8 inclusive wherein the consolidating member is in the form of a positively rotated - pressure - wheel rings different and widely varying, as to the composition and density of the metal, may be produced by varying the pressure and densifying and consolidating action through the manipulation of the tension screws 21; or by varying the rapidity of rotation of the 60 pressure-wheels 30, or of the cathode C—,

or by a combination of any two, or of all three of same; and it is preferable to rapidly rotate the pressure wheels 30; the rapidity of rotation differing with the character of the particular metal at the moment being 70 deposited.

As shown herein where pressure-wheels are used the same are usually and preferably rotated as shown by the arrow reversely to the rotation of the cathode and the ring 75 being deposited and densified; but in cases where the metal is of such quality as to be liable to strip, this may to a large extent be prevented by rotating such pressure-wheels 30 in the same direction as the cathode and 80 rings being deposited, but at a higher rate of peripheral speed, such rate of rotation being dependent upon the character of the metal.

The process for the removal of the deposited articles, in this case rings; from the depositing blanks or mold-rings, forms no particular part of this process, and is fully set forth, described and claimed in my beforementioned copending application, 90 and I have therefore not deemed it essential to more fully describe the same herein.

I have found in practice that in order to form the rings of exceedingly smooth end surface whereby the same when finished will 95 need no tooling or dressing, it is preferable to form the insulating mold-blank-rings 14 of glass, porcelain or any other exceedingly hard-substance with a very smooth surface, which will not be affected by the action of 100 the liquid in the bath; and in some cases, and for certain purposes, the consolidated ring may be also formed of like material.

I claim:—

1. The hereinbefore described process for 105 the formation of metallic articles which consists of the following steps:—(1) forming a conducting - mold - blank; (2) positioning such mold-blank upon and in contact with a cathode; (3) positioning insulation upon 110 the cathode to wall such mold-blank to form a molding-cavity outward of such mold-blank; (4) immersing the cathode in an electrolytic-bath; (5) electrolytically depositing upon the face of the conducting-mold-blank the required quantity of deposition to 115 form the article desired to be produced; (6) during such deposition subjecting the deposition to mechanical smearing or burnishing pressure so as to by such pressure consolidate, densify and compact the same so as to form a homogeneous metallic structure; (7) removing the conducting mold-blank and article from the cathode; and (8) separating the mold-blank from the article. 120

2. The hereinbefore described process for the formation of metallic rings, which consists of the following steps:—(1) forming an annular conducting-mold-blank or ring, or a plurality thereof; (2) positioning the 125

same upon and in contact with the periphery of a cylindrical-conducting-cathode; (3) interposing upon such cylindrical-cathode insulating-rings to form an annular mold-
 5 ing-cavity outward of the peripheral surface of each of such mold-blank-ring or rings; (4) immersing the cathode so supplied in an electrolytic depositing bath; (5) electrolytically depositing upon the face of the con-
 10 ducting-mold-blank ring or rings within the insulating rings the required quantity of deposition to form the ring or rings desired to be produced during rotation of the cathode; (6) during such deposition subjecting
 15 the deposition to mechanical smearing or burnishing pressure so as to by such pressure consolidate, densify and compact the same so as to form a homogeneous metallic structure; (7) removing the conducting-mold-blank or
 20 blanks, article or articles from the cathode; and (8) separating the two.

3. In a device of the class described, an electrolytic-bath-tank or receptacle adapted to contain electrolytic fluid; an electrolytic-
 25 cathode located in the tank; an electric-anode also located in the tank; a conducting-mold-blank or blanks positioned on and in contact with the cathode; walls of insu-
 30 lating material adjacent to the mold-blank or blanks, also mounted on the cathode ex-
 tending beyond the mold-blank or blanks to form a deposition cavity or cavities wherein the article or articles required to be pro-
 35 duced may be electrolytically deposited; and means for compressing the foliated electro-
 lytically deposited laminæ during such dep-
 osition, by a smearing and burnishing pres-
 sure.

4. In a device of the class described, a
 40 receptacle adapted to contain an electrolytic-
 fluid; an anode located in the receptacle;
 a cathode adapted to be removably and revo-
 lubly mounted in the receptacle; a plurality
 of conducting-mold-blanks in contact with

such revoluble cathode carried thereby; 45 walls of insulating material walling the mold-blanks, and extending beyond the outer surface thereof so as to form molds of the shape and contour of the articles desired to be electrolytically produced; means for me-
 50 chanically compressing the foliated electro-
 lytically deposited laminæ during such dep-
 osition by a smearing and burnishing pres-
 sure; and means for moving the cathode and
 55 its accompanying mold-blank or blanks in the bath, during such deposition and me-
 chanical compression and consolidation.

5. In a device of the class described, a tank or receptacle for holding an electro-
 lytic-depositing bath; an anode located in 60 said receptacle; a cathode located in such re-
 ceptacle removably and revolubly mounted in such receptacle; an annular conducting mold-blank-ring, or a plurality thereof, lo-
 65 cated upon and in contact with the periph-
 ery of the cathode; and insulating rings also
 mounted upon the cathode, and extending
 beyond the outer peripheral surface of such
 conducting mold-blank-ring or rings so as
 70 to leave a cavity or cavities of the form of
 the ring or rings to be deposited; a source
 of electrical supply connected with the cath-
 ode and anode; means for rotating the cath-
 ode; and a revolubly mounted wheel or
 75 wheels fitting in the molding-cavity or
 cavities exerting mechanical pressure upon
 the rings being electrolytically deposited
 therein, during the rotation of the cathode,
 which pressure wheels are rotated reversely
 80 to the rotation of the cathode, with a yield-
 ing pressure so as to compact, densify and
 consolidate the foliated laminæ being de-
 posited while in a substantially nascent state
 during such deposition.

EDWARD G. COOK.
